UNITED STATES PATENT OFFICE.

ROYAL L. BOULTER, OF LOS ANGELES, CALIFORNIA.

TELEGRAPH-KEY.

1,074,831.

Specification of Letters Patent.

Patented Oct. 7, 1913.

Application filed August 13, 1912. Serial No. 714,794.

To all whom it may concern:

Be it known that I, ROYAL L. BOULTER, a citizen of the United States, residing at Los Angeles, county of Los Angeles, and State 5 of California, have invented certain new and useful Improvements in Telegraph-Keys, of which the following is a specification.

This invention relates to telegraph keys. 10 The present invention relates to that class of telegraph keys known as "transmitters" or "vibrators" which employ a vibratory reed or pendulum in connection with a key for the purpose of making the dots to relieve the operator of the repeated finger and 15 wrist movements necessary with the ordinary telegraph key when making a series of dots. This class of transmitter also employs a separate key for forming dashes. 20 The two keys are, in most transmitters at present known to the art, arranged for movement laterally or sidewise, as contradistinguished from the up and down movement of the old type of telegraph key, and 25 they are particularly designed for sending messages rapidly with a minimum effort on the part of the operator, but are particularly useful to operators having writer's cramp or telegrapher's paralysis. Hereto- 30 fore transmitters of this type, while superior in many respects to the old style Morse key, have been incapable of such adjustment as to adapt them for both fast and slow work and for use on both long and 35 short lines; they have been subject to the involuntary formation of what operators term "split" dots owing to the quick vibrations of the vibrator or reed which occur before the lever is released, particularly in 40 letters of the alphabet having but one dot such as "A" and "N"; and they have usually also been complicated, have occupied considerable space and are liable to derangement.

45 The present invention has for its object the provision of a transmitter or vibrator telegraph key which will be simple, compact, strong, durable, susceptible of any desired adjustment of the contacts, and particularly those used for forming dots.

50 Another object of the invention is the provision, in a telegraph transmitter or vibrator, of novel, adjustable dot producing means combined with a vibrator in a new

manner and susceptible of adjustment with- 55 in a wide range which will be adapted to make a single dot as in the ordinary or Morse key, the vibrator having nothing to do with the making of a single dot, and to produce a plurality of dots automatically 60 without possibility of sending split dots.

The dot making mechanism embodies means whereby the electrical circuit is closed through the contacts except when periodically opened automatically by the 65 vibrations of the vibrator due to the new contact employed and the new manner in which the vibrator co-operates with said contact, whereby the circuit is automatically and regularly opened by the vibrations of 70 the vibrator with short intermittent interruptions. This construction results in closing of the circuit for a maximum of time and the sending of the longest and heaviest dots possible, so far as I am aware, in any vibratory transmitting telegraph instrument. At 75 the same time, the construction is such that a single dot is formed as with an ordinary Morse key.

The instrument is adapted for slow or 80 fast work and on either short or long circuits.

One embodiment of the invention is set forth fully hereinafter and the novel features thereof are recited in the appended 85 claims.

In the accompanying drawings:—Figure 1 is a plan view; Fig. 2, a side view; Fig. 3, a bottom plan view; and Figs. 4 and 5, detail sectional views.

The base 1 is preferably of metal to form a part of the circuit, one of the binding posts 2 being connected thereto, the other binding post 3 being insulated therefrom. The adjustable dash contact 4 and the adjustable dot contact 5 are in circuit with the binding post 3 by the connections 6. A circuit closer is shown at 7.

Suitably secured to the base 1 is a metallic box 8. The dot lever 9 and the dash 100 lever 10 have trunnions 11 and 12, respectively, which are pivoted to the box 8, said levers lying within the said box and being provided with finger-pieces or keys 13 and 14 suitably secured thereto and of insulating material, preferably of a certain degree of flexibility to cushion the pressure of the fingers of the operator. The respective le-

vers have lugs 15 and 16 which are adapted to engage the box 8 and limit the return movement of the levers, these lugs acting as stops. An adjustable screw 17 threaded 5 through the side of box 8 is also adapted to limit the play of the dot lever 9. An adjustable screw 18 and a spring 19 regulate the tension exerted on the dot lever and a similar screw and spring 20 and 21 perform 10 a corresponding function in reference to the dash lever 10. The dash lever carries a contact 22 which engages the dash contact 4 on the base 1.

The dot lever 9 is provided with an upward extension 24 having arms to which are connected leaf springs 25 to which in turn is connected a cross-piece 26. Suitably secured to this cross-piece, in an adjustable manner, if desired, is a rod 27 on which is 15 an adjustable weight or bob 28. The rod 27 has an extension or arm 29 preferably provided with a small roller 30. The mechanism just described constitutes a vibrator which, if the operator's finger be allowed 20 to remain against the key 13 after pressure thereon, is set into vibration, the amplitude and rapidity of which is controlled by the position of the adjustable weight or bob 28. On the base 1 there is provided a post 31 25 having a clamping screw 32 by which a stop 33 may be secured in any desired position of lateral adjustment, said stop being preferably provided with a roller 34 having a loose pivotal or axial connection with the stop and adapted to be engaged by the rod 27 when the pressure is released on the key 13 to thereby immediately bring the vibrator to a state of rest.

Slidable through an opening in the upward extension 24 of the dot lever is a tubular stem 35 which may be held in any desired position by a screw 36. Pivoted at 37 to an arm 38 on the stem 35 is an angular contact 39 which is provided with a platinum tip 40 adapted to engage the dot contact 5. Screw-threaded through the other arm of the contact is an anvil screw 41 which is adapted for any desired adjustment and for engagement by the tapping 40 thereon of the roller 30 of the tapper arm 29. The contact 39 has a lug 42 adapted to cooperate with the arm 38 on the stem 35 to limit the play of said contact. Extending through the tubular stem 35 is a spring 43 45 whose extent of compression may be regulated by a screw 44 threaded into said stem 35, said spring bearing against the contact 39 and tending to properly position it and to cushion said contact to permit it to vibrate in producing a plurality of dots under the tapping action produced on the anvil screw 41 when the vibrator is vibrating.

The forefinger is used to operate the dash key 14 and the thumb the dot key 13, the 60 movement of the hand being in a general

lateral direction as contradistinguished from the general vertical direction used in operating the old style Morse key. When a dash is to be formed, the key 14 is pressed. When a single dot is to be formed, the key 13 is tapped or pressed with the thumb, whereupon the dot lever 9, the vibrator composed of the springs 25, the rod 27, and the angular contact 39 move as an entirety for the formation of a single dot. If, however, a plurality of dots are to be formed, the pressure of the thumb on the key 13 is maintained, whereupon the inertia imparted to the vibrator consisting of the springs 25 and the rod 27, causes the latter to be set into vibration which is more or less slow or fast according to the position of the weight on the rod 27. In this operation, the platinum tip 40 is first brought against the dot contact 5, but the vibrator having been set in motion, the tapper arm 29 and the roller 30 cause repeated taps or blows to be delivered on the anvil screw 41 against the cushioning action of spring 43, thereby momentarily separating the platinum tip 40 from the dot contact 5 and producing the plurality of dots desired, according to the period the key 13 is under pressure. Upon the release of the key 13, the rod 27 by striking against the roller 34 immediately brings the vibrator to a position of rest.

As a result of this construction, I am able to produce, so far as I am aware, the longest and heaviest dots which it has been possible to make on a transmitter key as the circuit is closed for a maximum of time during the travel of the vibrator and I thereby avoid the formation of split dots, but at the same time gain all the advantages of the formation of a single dot without any danger of splitting the dot in that event.

It will be observed that in the formation of dots, the operation is different from that in vibrating transmitters heretofore known, as the movement of the key on the application of pressure thereon at once effects an initial positive engagement of the dot sending contacts.

Having thus described my invention, what I claim as new and desire to secure by Letters Patent, is:—

1. In a telegraph transmitter, the combination with an operating key, of a movable spring cushioned contact adapted to be operated thereby, and a vibrator also adapted to be operated by the key in addition to the adaptability of the key to operate the spring cushioned contact and arranged and adapted to tap or actuate the contact in opposition to the spring cushioned action thereof.

2. In a telegraph transmitter, the combination with an operating key, of a contact pivoted thereto and bodily movable therewith, spring means for cushioning said contact, and a vibrator carried by the key and

arranged and adapted to tap or actuate the contact in opposition to the spring cushioned action thereon.

3. In a telegraph transmitter, the combination with an operating key, of a movable contact carried thereby, a vibrator also carried by the key, and an adjustable tappet device interposed between the contact and the vibrator, whereby the vibrator is adapted to deliver taps on said contact.

4. In a telegraph transmitter, the combination with an operating key, of a movable contact carried thereby, a vibrator also carried by the key, an adjustable tappet device interposed between the contact and the vibrator, whereby the vibrator is adapted to deliver taps on said contact, and an adjustable spring cushion for said contact.

5. In a telegraph transmitter, the combination with an operating key, of a contact pivoted to the key and also having an ad-

justable connection therewith, whereby it may be moved as an entirety in relation to the key.

6. In a telegraph transmitter, an operating key, in combination with a stem adjustably carried thereby, a contact pivotally mounted on the stem, and a spring tension device for said contact.

7. In a telegraph transmitter, an operating key, in combination with a stem adjustably carried thereby, a contact movably mounted on the stem, and a spring tension device for said contact embodying a spring extending through the stem, and a screw for regulating the tension on said spring.

In testimony whereof, I hereunto affix my signature in presence of two witnesses.

ROYAL L. BOULTER.
